Primary Examiner — Kimberly Barnes(57) **CLAIM**

The ornamental design for a tripillow, as shown and described.

DESCRIPTION

FIG. 1 is a front, left side perspective view of a tripillow showing my new design.

FIG. 2 is a front view of a tripillow as shown in FIG. 1.
 FIG. 3 is a back view of a tripillow as shown in FIG. 1.
 FIG. 4 is a top view of a tripillow as shown in FIG. 1.
 FIG. 5 is a bottom view of a tripillow as shown in FIG. 1.
 FIG. 6 is a left side view of a tripillow as shown in FIG. 1; and,
 FIG. 7 is a right side view of a tripillow as shown in FIG. 1.

The broken lines in FIGS. 1, 2 and 3 depict portions of the tripillow that form no part of the claimed design.

1 Claim, 5 Drawing Sheets(56)
